UNITED STATES PATENT OFFICE

157,795

VACUUM INSULATED PITCHER OR
SIMILAR ARTICLE

Eugene Schwarz, Alexandria, Ind., assignor to
Aladdin Industries, Incorporated, Chicago, Ill.,
a corporation of Illinois

Application August 4, 1948, Serial No. 147,933

Term of patent 14 years

(Cl. D44—21)

To all whom it may concern:

Be it known that I, Eugene Schwarz, a citizen of the United States, residing at Alexandria, in the county of Madison and State of Indiana, have invented a new, original, and ornamental Design for Vacuum Insulated Pitcher or Similar Article, of which the following is a specification, reference being had to the accompanying drawings, forming part thereof.

Fig. 1 is a perspective view of a vacuum insulated pitcher or similar article, showing my new design with the lid in closed position; and

Fig. 2 is another perspective view thereof with the lid in open position.

I claim:

The ornamental design for a vacuum insulated pitcher or similar article, as shown.

EUGENE SCHWARZ.
